UNTERNEHMUNGEN, OF BADEN, SWITZERLAND.

ELECTRIC FURNACE

Application filed February 8, 1921. Serial No. 443,406.

To all whom it may concern:

Be it known that I, ARTURO PAOLONI, a subject of the King of Italy, residing at Baden, Switzerland, have invented certain new and useful Improvements in Electric Furnaces; and I do hereby declare the following to be a clear, full, and exact description of the invention, such as will enable others skilled in the art to which it appertains to make and use the same, reference being had to the accompanying drawings, and to letters or figures of reference marked thereon, which form a part of this specification.

This invention relates to improvements in electric furnaces.

The difficulty experienced heretofore in constructing an electric furnace working on a large scale for baking refractory materials consisted mainly in obtaining inside the heating chamber which must necessarily be comparatively large and charged with these materials a very high temperature which is as nearly as possible uniform in all the parts of the heating chamber. Further it is of importance that the heating chamber is entirely independent of the electric current and the electrodes.

The object of the present invention is an electric furnace with a heating chamber which chamber is characterized by the feature that it is separated from the electrodes and the electric current by at least one wall which is infusible and a good conductor of heat, opposite to which wall and at the outer side thereof the electric resistance (the so-called resistor) is arranged. The heat produced by the resistor is utilized for heating the chamber which heating is effected partly by the radiation of said wall and by conducting the heat into the heating chamber by means of suitably shaped channels formed in this wall.

Several modes for carrying the invention into effect are shown by way of example in the accompanying drawings, in which:

Figs. 1 and 2 show a vertical and a horizontal section respectively through a first constructional example;

Figs. 3 and 4 are vertical and horizontal sections through a second constructional example;

Fig. 1^a is a vertical section through a third

constructional example illustrating a modification to the construction shown in Figs. 55 1 and 2;

Fig. 2^a is a horizontal section through the furnace shown in Fig. 1^a,

Figs. 1^b and 2^b illustrate vertical and horizontal sections of a fourth constructional 60 example.

Figs. 3^a and 4^a are vertical and horizontal sections through a fifth example which is a modification of the construction illustrated 65 in Figs. 3 and 4.

Figs. 3^b and 4^b are corresponding sections through a sixth example being a further modification of the construction shown in Figs. 3 and 4.

In the electric furnace illustrated in Figs. 70 1 and 2, the electric energy is transformed by means of the resistors, each of which consists of a core 10 made of compressed carbon or ordinary carbon, the resistors being connected to the electrodes 6 which are connected to the mains. The core 10 is surrounded by carbon or granulous graphite.

In accordance with the Joule-effect of the electric current the whole resistance is heated up to a maximum temperature of 80 2200° C., lower temperatures may be obtained at will by regulating the tension. Each resistor is arranged in between four side walls, two of which are opposite to each other, the electrodes 6 passing through said walls.

The other two side walls 9 and 2 or 3 respectively are also opposite each other and consist of different material, the wall 9 serves for thermal insulation purposes, whereas the wall 2 or 3 respectively is a conductor of heat and is generally made of compressed carborundum combined with tar. The walls 2 and 3 form at the same time the walls of the heating chamber 1. This material can stand a temperature of 90 2000° C. without melting and without decomposing and its conductivity of heat is approximately four times as high as that of the best refractory brick, which brick moreover melts at a much lower temperature and 95 is attacked by the glowing carbon of the resistor.

In order to obtain a maximum of heat transmission from the resistor to the heating chamber through the walls 2 and 3 the latter are provided with cavities or channels 4. 100 105

105

These channels connect the resistor with the heating chamber for the purpose of facilitating the transmission of heat into the chamber 1. By this arrangement a temperature of from 1400 to 1500° C. may be produced inside the chamber 1, which temperature is necessary when baking porcelain. In the present case the so-called Stephan-Boltzmann principle is thus made use of, according to which the total of the energy radiated is in direct proportion to the fourth power of the absolute temperature. Through the channels 4 the heat radiates directly into the heating chamber 1 and important calorific currents are thus produced which flow into the heating chamber 1. Owing to the provision of said channels the calorific energy obtained by the transformation in the resistor of the electric energy into heat according to the Joule-effect, will preferably through the intermediate of these channels be conveyed into the interior of the chamber 1.

In all the cases in which it is intended to avoid that the material of which the resistor is made is exposed to the chemical action of volatile gases especially of carbonic acid dissociating from the products to be baked, the channels 4 provided in the heat conducting walls may be closed by means of thin diaphragms 7, which prevent the gases developed from reaching the resistor (Figs. 1^a and 2^a).

A furnace with a single chamber constructed on the aforementioned lines and heated by two resistors connected in series is illustrated in Figs. 1 and 2. The channels 4 provided in the walls 2 and 3 are open at both ends in this case and may be of cylindrical cross-section. The upper part of the two resistors and the heating chamber are covered by refractory plates. The carbon or the granulated graphite of the resistor may also be covered by a layer of siliceous sand. If the insulation around the furnace is made properly the thermal efficiency is very high.

A similar furnace to that shown in Figs. 1 and 2 is illustrated in Figs. 1^a and 2^a, the distinguishing feature being that the channels 4 provided in the side walls 2 and 3 are closed against the resistor by means of a diaphragm 7 whilst the cross-sectional area of the channels increases towards the heating chamber 1. This type of furnace may be worked with single phase as well as with continuous current.

Figs. 1^b and 2^b illustrate a constructional example of a furnace provided with three resistors for three phase current, whereby two chambers 1 are heated; the cross-sectional area of the channels 4 increases towards the heating chamber, but there are no diaphragms provided at the ends of the channels. It is evident that a furnace could

be constructed consisting of six resistors and five heating chambers 1 and this arrangement is the most economical.

In the furnace illustrated in Figs. 3 and 4 a number of pipes 8 open at both ends and the cross-section of which may be cylindrical, are provided in each resistor and lead into the heating chamber 1. These pipes 8 may be made of compressed carbon or better of compressed graphite and are surrounded by the carbon or the granulated graphite of the resistor and form a part of the resistor. The pipes act in the same manner as the channels described above. The pipes could also be constructed so that the cross-sectional area increases towards the heating chamber 1. The pipes may also be closed at their one end by means of a thin diaphragm, as is shown in Figs. 3^a and 4^a. The constructional example illustrated in these figures is built for single phase current and is provided with two resistors, in which pipes 8 are arranged which terminate within the resistor with their closed ends.

Figs. 3^b and 4^b illustrate an arrangement for a furnace for three phase current, in which the pipes 8 are closed at their one end by means of diaphragms 7 and are embedded with their closed ends in the resistor. The centre resistor 5 is, however, provided with pipes 8 open at both ends and terminating into both chambers 1.

The furnaces described above respond to all requirements of the ceramic industry with regard to furnaces. Objects of porcelain may be subjected to a first baking process at a temperature of from 800 to 900° C. by working the resistors with a lower tension and connecting a plurality of resistors in series. For the second baking period at a temperature of from 1400 to 1500° C. the tension is increased and the resistors are connected in parallel.

As the heating chamber is entirely independent of the electric current and of the electrodes it is easy to construct a kiln of the tunnel type for baking bricks. The objects to be baked, such as limestone, glass, cement, magnesian limestone, magnesite, refractory earth and bricks, clay-bricks, may be charged either directly into the chamber 1 or into muffles in which electrodes, objects of porcelain and the like may be treated. With a large muffle different chemical and metallurgical processes may be carried out amongst which also the processes for treating solid objects at a high temperature with nitrogen. The furnaces may also serve for heating iron and steel blocks to a high temperature or for other purposes in producing iron or steel.

Claims:

1. In an electric furnace having a heating chamber, a resistor solely acting as heat

- producer, an infusible, heat-conducting wall separating said resistor from a heating chamber and having channels therethrough, a thin diaphragm closing said channels to-
wards the resistor to prevent circulation of gases between the resistor and the heating chamber and vice versa, thereby increasing the transmission of heat from the resistor to the chamber.
- 10 2. In an electric furnace having a heating chamber, a resistor solely acting as heat producer, an infusible heat-conducting wall separating said resistor from said heating chamber, and horizontally arranged pipes of refractory material, which pass at least partly through the resistor being provided in said walls for increasing the transmission of heat from the resistor to the chamber.
- 15 3. In an electric furnace having a heating chamber, a resistor solely acting as heat producer, an infusible heat-conducting wall separating said resistor from said heating chamber, and horizontally arranged pipes of refractory material, which pass at least partly through the resistor being provided
- in said walls for increasing the transmission of heat from the resistor to the chamber, and a thin diaphragm closing the end of each pipe towards the resistor to prevent circulation of gases between the resistor and the heating chamber and vice versa.
4. In an electric furnace having a heating chamber, a resistor solely acting as heat producer, an infusible heat conducting wall separating said resistor from said heating chamber, and horizontally arranged pipes of carbonaceous material passing through said walls for increasing the transmission of heat from the resistor to the chamber.
5. In an electric furnace having a heating chamber, a resistor solely acting as heat producer, an infusible heat-conducting wall separating said resistor from said heating chamber, and horizontally arranged graphite pipes for increasing the transmission of heat from the resistor to the chamber.

In testimony that I claim the foregoing as my invention, I have signed my name.

ARTURO PAOLONI.
